ATTORNEY.

UNITED STATES PATENT OFFICE.

JOSEPH HAY AMIES, OF PHILADELPHIA, PENNSYLVANIA.

HIGHWAY AND SIMILAR FOUNDATION.

Application filed February 16, 1921. Serial No. 445,532.

To all whom it may concern:

Be it known that I, JOSEPH HAY AMIES, a citizen of the United States, residing at the city of Philadelphia, in the county of Philadelphia and State of Pennsylvania, have invented a certain new and useful Highway and Similar Foundations, of which the following is a specification.

This invention generally stated relates to the building of highway foundations and has more especial relation to the construction of what are commonly termed concrete highway foundations.

As at present practiced, so called concrete road-beds are generally unsatisfactory, particularly when required to sustain considerable motor-vehicle traffic. Experience demonstrates that the sub-grade of a highway, even when thoroughly rolled, will under considerable motor-vehicle traffic, acquire depressions in a more or less uneven manner. The bed of concrete superimposed upon such sub-grade, being hard, brittle and unsupported where such depressions occur, will crack under sustained motor-vehicle traffic. Experience demonstrates that poor highway conditions result quite as frequently from this cause as from frost attacking the sub-grade with consequent expansion and contraction thereof.

The leading object of the present invention may be said to reside in the method of building a highway or like foundation in which not only is the road-bed prevented from creeping or shifting with respect to the sub-grade but by its unique structure precludes the possibility of frost attacking the sub-grade.

Other and further objects will hereinafter appear.

The invention consists of improvements hereinafter described and finally claimed.

The nature, characteristic features and scope of the invention will be more fully understood from the following description taken in connection with the accompanying drawings forming part hereof and in which:—

Fig. 1, is a top or plan view of a section of highway illustrating two horizontal planes thereof.

Fig. 2, is a view in transverse section taken upon the line 2—2 of Fig. 1.

Fig. 3, is a similar view taken upon the line 3—3 of Fig. 1.

Fig. 4, is a fragmentary view in longitu-

dinal section illustrating the construction of a transverse drain.

Fig. 5, is a view in transverse section illustrating a slightly modified form of buttress construction.

Fig. 6, is a fragmentary view of a further modified form of drain.

Fig. 7, is a similar view of a still further modified form of drain.

For the purpose of illustrating my invention I have shown in the accompanying drawings one form thereof which is at present preferred by me, since the same has been found in practice to give satisfactory and reliable results, although it is to be understood that the various instrumentalities of which my invention consists can be variously arranged and organized and that my invention is not limited to the precise arrangement and organization of the instrumentalities as herein shown and described.

While in the drawings a highway foundation is shown and the following description, for illustrative purposes is restricted thereto, obviously the principles of the present invention are applicable to other structures embodying a sub-grade and a cementitious super-structure.

In practicing the present invention the sub-grade 10 if necessary is first thoroughly rolled to secure necessary compactness and an even surface. A longitudinal trench 11 is then formed along each side of the highway throughout its extent. In practice one of these trenches is dug deeper than the other. As an example, good results have been obtained by forming one trench about 20" below the sub-grade surface and the other about 30" below the sub-grade surface.

At suitable intervals throughout the length of the highway these longitudinal trenches are connected by forming transverse trenches 12.

These transverse drains may occur every 25' or 50' as desired and incline from the relatively shallow to the relative-deep longitudinal ditch. In practice the ditches 11 and 12 are formed substantially V-shaped.

These trenches may now be partially filled with relatively small stones, broken stone or equivalent material 13 as shown in Figs. 1 to 5 inclusive. At least from 6" to 10" of space should be left between the upper face of the sub-grade and the upper level of the material placed within the trenches. There is next formed in the sub-grade, between the transverse trenches, a plurality of spaced

cavities or openings 14 as clearly shown at the left hand side of Fig. 1. However, the particular configuration of opening is immaterial and may be substantially V-shaped 5 as shown in Fig. 5. A cementitious material 15 of any desired type is now spread over the sub-grade 10 to a desired thickness and caused to fill the cavities or openings 14 and the space within the trenches 11 and 10 12 unoccupied by stone filling 13. The trenches 11 so filled with cementitious material form buttresses 16 for supporting the arch of the road bed. The transverse trenches so filled form beams 17 for sustaining weight which would otherwise rest upon the sub-grade. The cavities or openings 14 so filled form buttresses 18 which function to evenly distribute weight of traffic over the sub-grade. That part of a 15 trench below the cementitious filling of course serves to facilitate proper drainage which is essential to proper highway construction. In this connection it will be understood that water passes from the upper or shallow trench to the lower or deeper trench through the transverse trenches thus draining efficiently the sub-grade beneath the highway. If desired the transverse trenches may be extended through the deepest longitudinal trench for a short distance, 20 as shown in Fig. 2, in order to more effectively drain the sub-grade. Not only do the trenches form an effective system of drainage but frost is prevented from attacking the sub-grade. This is true because the trenches form air-chambers which preclude frost passing thereto through to the sub-grade. This is a very important point in highway construction in that freezing and thawing of the sub-grade soon ruins the highway super-structures. As shown in 25 Figs. 1 and 3, anchors 17, usually of steel, are provided. These anchors are driven down through the cementitious super-structure into the buttresses 18 in some instances and in other instances partially through these buttresses into the sub-grade before the initial set of the cementitious material takes place. Such anchors function to securely 30 hold the super-structure with respect to the sub-grade. These anchors also serve to dissipate shock and vibration of traffic.

In Fig. 6, there is shown a slightly modified form of trench construction. The stone filling is omitted and there is extended across the trench and anchored in the soil of the road a stiff wire mesh 20. The cementitious material is then poured in the trenches as above described. Thus the trenches may be 35 open for the free flow of water.

In Fig. 7, the wire mesh 21 may be so curved that the ends thereof are caused to rest upon the bottom of the trench. This allows the cementitious composition to rest 40 between the wire mesh and the sides of the

drain and also to rest upon the bottom of the trench.

It will now be apparent that I have devised a novel and useful construction which embodies the features of advantage enumerated 45 as desirable in the statement of the invention and the above description and while I have in the present instance shown and described the preferred embodiment thereof which has been found in practice to give 50 satisfactory and reliable results, it is to be understood that the same is susceptible of modification in various particulars without departing from the spirit or scope of the invention or sacrificing any of its advantages. 55

What I claim is:

1. A foundation of the character stated comprising a sub-grade provided along each side thereof with a trench of which one is relatively deep and the other relatively 60 shallow, a plurality of other trenches extended transversely through the sub-grade and inclining from the shallow toward the deeper of and communicating with the longitudinal trenches, and a cementitious super-structure for said sub-grade the material of 65 which partially fills said trenches to form buttresses for supporting the arch of the road bed and means within said trenches for supporting said cementitious material free 70 of the trench bottoms for drainage purposes.

2. A construction as described in claim 1, characterized by a plurality of spaced buttresses of cementitious material located in 75 the sub-grade.

3. A construction as described in claim 1, characterized by a plurality of spaced cementitious buttresses located in the sub-grade and a metallic anchor for each buttress for securing the super-structure to the 80 sub-grade.

4. A foundation of the character stated comprising a sub-grade provided along each side thereof with a trench of which one is relatively shallow and the other relatively 85 deep, a plurality of other trenches extended transversely through the sub-grade and inclining from the shallow toward the deeper trench and communicating with said longitudinal trenches which latter trenches are at 90 least partially filled with broken stone or equivalent material to provide firm, unyielding bases, and a cementitious super-structure for said sub-grade the material of 95 which rests upon such bases to form buttresses for supporting the arch of the road bed.

5. A construction as described in claim 4, characterized by said longitudinal trenches being V-shaped to resist shock and attrition 100 of traffic.

6. A construction as described in claim 5, characterized by a plurality of spaced compartments in the sub-grade which are filled 105

with said cementitious material simultaneously with the arched super-structure in order to secure unison of set whereby the arched super-structure is held to the but-
5 tresses thus formed.

7. A construction as described in claim 4, characterized by anchors for holding the

arched super-structure with respect to the sub-grade and to accept shock and attrition of traffic and refer same to the sub-grade. 10

In testimony whereof, I have hereunto signed my name.

JOSEPH HAY AMIES.
